Primary Examiner — Susan Moon Lee(74) *Attorney, Agent, or Firm* — Dunlap, Bennett & Ludwig PLLC**CLAIM**

The ornamental design for a pet bowl, as shown and described.

DESCRIPTION

FIG. 1 is a top front perspective view of a pet bowl;
 FIG. 2 is a front elevation view thereof, the rear elevation view
 being a mirror image thereof;
 FIG. 3 is a left side elevation view thereof, the right side
 elevation view being a mirror image thereof;
 FIG. 4 is a top plan view thereof; and,
 FIG. 5 is a bottom plan view thereof.
